UNITED STATES PATENT OFFICE.

JAMES W. PLIMPTON, OF OIL CITY, PENNSYLVANIA.

ROTARY GAS-ENGINE.

SPECIFICATION forming part of Letters Patent No. 683,705, dated October 1, 1901.

Application filed April 24, 1900. Serial No. 14,162. (No model.)

To all whom it may concern:

Be it known that I, JAMES W. PLIMPTON, a citizen of the United States of America, residing at Oil City, in the county of Venango and State of Pennsylvania, have invented certain new and useful improvements in Gas-Engines, of which the following is a specification, reference being had therein to the accompanying drawings.

10 This invention relates to certain new and useful improvements in gas-engines; and it aims to construct an engine of this character to overcome the uneven irregular power production and transfer which is usual in engines of this class.

15 The invention further aims to construct an engine which shall be extremely simple in construction, strong, durable, efficient in its operation, and comparatively inexpensive to 20 set up.

The invention consists in the novel construction, combination, and arrangement of parts to be hereinafter more fully described, and specifically pointed out in the claims.

25 In describing the invention in detail reference is had to the accompanying drawings, forming a part of this specification, and wherein like numerals of reference indicate corresponding parts throughout the several views, 30 in which—

Figure 1 is an end view of my improved engine. Fig. 2 is a side view thereof. Fig. 3 is a longitudinal sectional view thereof. Fig. 4 is an end view, partly broken away, showing 35 one end of the housing in vertical section. Fig. 5 is a vertical sectional view of one portion of the drive wheel or disk, showing the explosion-chamber. Fig. 6 is a longitudinal sectional view of the sliding-plunger abutments. Fig. 7 is a perspective view thereof. Fig. 8 is a sectional view taken on the line 40 8 8 of Fig. 5. Fig. 9 is an enlarged vertical sectional view of one end of the housing. Fig. 10 is an enlarged vertical sectional view of 45 the igniter.

Referring to the drawings by reference-numerals, 1 and 2 indicate the sections of the housings, mounted upon a suitable base 3. Each of the housings has formed integral 50 centrally thereof with their outer faces an auxiliary housing 4, provided near the top thereof with a longitudinal opening 5, which extends entirely through the same. The sections of the housings are suitably secured to

the base by means of bolts 6 and secured together by a bolt 7 in such a manner as to permit of the turning therethrough of the drive wheel or disk 7'. The top of each of the auxiliary housings is provided with a longitudinal slot 8, and the sections 1 and 2 are each 60 provided with a suitable exhaust-opening 9.

Operating within the longitudinal opening 5 of the auxiliary housings are the sliding-plunger abutments 10 11, the plunger 10 having one face formed with a tenon 12, which 65 is adapted to be seated in the cylindrical recess 13, formed in the meeting face of the plunger 11. The plungers are each provided with a spring-pressed packing, which consists of two pieces of suitable flexible material 14, 70 connected together by the spring 15. This packing is seated within a suitable opening 16, arranged near the inner face of each of the plungers, and serves to prevent the explosive mixture passing around the plungers 75 when the latter are within any one of the explosion-chambers of the drive-wheel 7'.

Mounted upon the base 3 are a pair of standards 17, having journaled in their upper end by means of bearings 18 the drive-shaft 19, 80 which has suitably keyed thereon a drive wheel or disk 7'. Secured to the drive-shaft 19 at each side of the disk 7' are the collars 20, each of which is provided with an oppositely-arranged cam-groove 21.

85 Mounted upon each of the auxiliary housings 4 is a pair of uprights 22, to which is fulcrumed by means of the pin 23 an operating-lever 24. One end of this lever 24 is arranged within the cam-groove 21, while the 90 opposite end extends down through the slot 8 and is connected to the outer end of the sliding plungers, as at 25. Arranged upon the drive-shaft 19, at each side of the drive wheel or disk 7', are the gear-wheels 26, which 95 mesh with the gear-wheel 27, supported by the bracket 28, mounted upon the auxiliary housing. The outer face of the gear 27 has suitably connected thereto, as at 29, the piston-rod 30, carrying a piston-head 31 of the 100 feed-cylinder 32. This cylinder 32 is suitably secured to the upper face of the auxiliary housing 4, as at 33. Each of the auxiliary housings 4 is provided with an inlet-port 34, which is connected to a suitable source of air 105 and gas supply or other explosive mixture and opens at its inner end into the feed-cylinder 32. The inner end of each of these

ports is closed by means of the valve 35. Each of the auxiliary housings is further provided with an igniting-chamber 36, connected by means of the port or passage 37 to the 5 feed-cylinder 32. The upper end of this port or passage 37 is closed by a suitable flap-valve 38. The arrangement of the valves 35 and 38 is such that on the downstroke of the piston the valve 38 opens and the valve 35 closes. 10 The operation of the valves is reversed on the upstroke of the piston.

Extending down through each of the auxiliary housings is an electrical igniter 39, which is operated by trip-lugs 40 coming in 15 contact therewith and completing the electric circuit formed integral with the sides of the drive wheel or disk 7'. This electric igniter may be of any desired construction. The drive wheel or disk 7' is cast solid and the 20 rim thereof provided with a pair of ridges 41, suitably spaced apart and further provided with diametrically opposite openings 42, forming a pair of explosion-chambers. The inner faces of the sections 1 and 2 of the housings are cast with an annular recess, so that the rim of the wheel when operating through the housings will fit neatly within the recess, as shown in Fig. 3. The inner face of each of the sections of the housings is further provided with a suitable packing 43, which engages the rim of the wheel as the same passes therethrough. This packing may be of any preferred construction and is indicated in dotted lines in Fig. 4. One of the walls of 35 each of the explosion-chambers is tapered, as at 44.

The operation of my improved engine is as follows: Assuming that the piston has been brought to the position as shown, the explosive mixture drawn into the feed-cylinder, the valve 35 being open, as indicated in dotted lines, the drive-wheel being revolved will transfer motion by means of the gear-wheel 26 to the gear 27 to the piston-rod, 40 causing the same to force the piston downwardly, closing the valve 35, opening the valve 38, discharging the explosive mixture by means of the passage 37 into the igniting-chamber 36, and when the explosion-chamber 45 of the wheel or disk registers with the igniting-chamber 36 the explosive mixture will be forced into the explosion-chamber 42. During this operation the levers 22 will force the plungers together, as shown in Fig. 3, 50 and as soon as the plungers arrive at such position the trip-lug will engage the igniting mechanism and explode the charge, the force thereof revolving the wheel and imparting motion to the drive-shaft 19. As the drive-shaft revolves the plungers will be drawn from the explosion-chamber of the wheel or disk, so that they will not interrupt the passage thereof. This operation is caused by 55 means of one end of the lever operating the cam-groove 21. Of course it will be evident that one or more explosion-chambers can be arranged in the wheel, if desired, and the 60

trip-lugs arranged in proper position thereto, so that the ignition of the explosive charge will take place at the proper time. 70

It is thought the many advantages of my improved gas-engine can be readily understood from the foregoing description, taken in connection with the accompanying drawings, and it will be noted that various changes 75 may be made in the details of construction without departing from the general spirit of my invention.

Having thus fully described my invention, what I claim as new, and desire to secure by 80 Letters Patent, is—

1. In a gas-engine, a pair of housings connected together, auxiliary housings formed integral therewith, and provided with a longitudinal opening, a drive-shaft, a drive-wheel carried by said shaft and operating between the housings, explosion-chambers formed in the rim of said wheel, a pair of feed-cylinders mounted on the housing and connected to a suitable source of explosive supply, pistons 85 arranged in said cylinders, gearing connecting said pistons of said cylinders to the drive-shaft, ports connecting the feed-cylinders with the explosion-chambers in the drive-wheel, an igniter carried by the housing, and 90 means carried by the drive-wheel for engagement with the igniter to explode the charge, a pair of plunger-abutments operating in the longitudinal opening in the housing and in the explosion-chambers of the drive-wheel, 95 and pivoted operating-levers having their one end connected to the plunger-abutments, means carried by the drive-shaft for actuating the levers and operating the said plungers, 100 substantially as described. 105

2. In combination with a pair of housings connected together and provided with auxiliary housings having a longitudinal opening, a drive-shaft, a drive-wheel mounted on said shaft and provided in its rim with explosion-chambers, feed-cylinders mounted on said housings, pistons geared to said drive-shaft, 110 said cylinders being connected to a suitable source of explosive supply, ports connecting said cylinders with the explosion-chambers, 115 and valves arranged in said ports for controlling the passage of explosive mixture to the explosion-chambers, an igniter in communication with the explosion-chambers, means carried by the drive-wheel for operating said igniter, a pair of plunger-abutments 120 operating in the longitudinal opening of the housing, and spring-pressed packing carried by said abutments, pivoted operating-levers connected to the abutments, and means carried by the drive-shaft for operating said levers, substantially as described. 125

In testimony whereof I affix my signature in the presence of two witnesses.

JAMES W. PLIMPTON.
